PRINTED ENAMEL SURFACE RUG OR SIMILAR ARTICLE

Alben J. Milwid, South Plainfield, N. J., assignor to Con-goleum-Nairn Inc., a corporation of New York

Application July 16, 1953, Serial No. 26,000

Term of patent 14 years

(Cl. D92—17)

To all whom it may concern:

Be it known that I, Alben J. Milwid, a citizen of the United States of America and resident of South Plainfield, county of Middlesex, and State of New Jersey, have invented a new, original, and ornamental Design for a Printed Enamel Surface Rug or Similar Article, of which the following is a specification, reference being had to the accompanying drawing, forming a part hereof. The single figure is a plan view of a printed enamel surface rug or similar article showing my new design. The back of the rug is of conventional appearance.

I claim:

The ornamental design for a printed enamel surface rug or similar article, substantially as shown and described.
